(No Model.)

J. R. WRIGHT.

VEHICLE SPRING.

No. 338,905.

Patented Mar. 30, 1886.

UNITED STATES PATENT OFFICE.

JAMES ROBERT WRIGHT, OF PORTLAND, OREGON.

VEHICLE-SPRING.

SPECIFICATION forming part of Letters Patent No. 338,905, dated March 30, 1886.

Application filed December 23, 1885. Serial No. 186,541. (No model.)

To all whom it may concern:

Be it known that I, JAMES ROBERT WRIGHT, of Portland, in the county of Multnomah and State of Oregon, have invented a new and Improved Vehicle-Spring, of which the following is a full, clear, and exact description.

The object of my invention is to provide a new and improved vehicle-spring which is very elastic with a light or heavy load, is strong and durable, simple in construction, and is so constructed that the spring-plates are not subjected to any lateral or torsional strain, which spring at all times regulates itself to the weight imposed upon it.

15 The invention consists in the construction and combination of parts and details, as will be fully described and set forth hereinafter, and then pointed out in the claims.

Reference is to be had to the accompanying drawings, forming a part of this specification, in which similar letters of reference indicate corresponding parts in all the figures.

Figure 1 is a side view of my improved vehicle-spring. Fig. 2 is a plan view of the under side of the same. Fig. 3 is a cross-sectional view on the line $x-x$, Fig. 1. Fig. 4 is a cross-sectional view of my improved shackle. Fig. 5 is a side view of the same. Fig. 6 is a top view of the same. Fig. 7 is a detail view 30 of the bolt or pin in said shackle. Fig. 8 is a plan view of the under side of the lower section of the shackle. Fig. 9 is a detail sectional view.

This invention relates to springs which are mainly adapted for use on side-bar vehicles, and the springs will be described as used with such vehicles; but they can be used on other kinds of vehicles as well.

The steel lever A is curved throughout its entire length, has its inner end squared, and is tapered from said inner end to its outer end, which is provided with the eye A² for coupling the end of the lever with a vibrating shackle.

45 The inner end of each lever A is passed into a box, B, placed and held against the bottom C of the vehicle body or box in a manner that will be described hereinafter.

Each box B has an open and a closed end, and the inner end of the lever A rests against the closed end of said box, the bottom of the box being open. The lever A, passing through

the box B, prevents lateral and torsional strain in any parts of the spring-plates. The top of the end part, A', of each lever A is rounded slightly, so that the end part of the lever can rock in the box. The fulcrum of the lever remains stationary with a very light load, but commences to roll or change its position as the weight increases.

One or more flat spring-plates, D, are bolted to the under side of the end part, A', of each lever A, and said flat spring-plates are curved in the same manner as the spring-plates of wagon-springs of the usual construction. To the free end of each spring-plate D the end of one of a series of spring-plates, E, is pivoted or connected in the usual manner, which plates E have their opposite ends bolted to the top of the corresponding box, the ends of said spring-plates E being between the top of said box and the under side of the bottom C of the wagon body or box.

At the open end of the box B the lugs F project downward from the side edges of the box, and on the bottom edges of said lugs of each box the clip-yoke G is placed, through the ends of which the bolts H are passed, which are also passed through side lugs, I, on the upper sides of the box, the tops of the side lugs, I, projecting slightly above the top of the box B, so that the tops of said lugs I and the tops of the springs E are flush. A rubber band, G', is placed on the clip-yoke G, below the lever A. The bolts H are passed through apertures in the bottom of the box or body of the wagon, and through a plate, H', on the top of the floor or bottom of the vehicle body or box. Nuts H² are screwed on the ends of the bolts below the clip-yoke G. If desired, a U-shaped bolt may be used.

A tongue, J, projects from the upper surface of the end A' of each lever A through a slot, J', in the top of the box, through slots in the springs E, and into a mortise on the under side of the bottom C of the vehicle body or box, which tongue closes the end of the box B against dirt, dust, &c.

As shown in Fig. 1, the under sides of the rear or inner ends of the levers A and the upper sides of the closed or corresponding ends of the boxes B are curved slightly, so that for light loads the springs can bend on the under sides of the levers and on the tops of the boxes

nearly up to the bolts holding the ends of the springs on the levers and boxes. As previously stated, the tops of the end parts, A', of the levers are also rounded, so as to work 5 easily on the under sides of the tops of the boxes B.

The lugs I give the boxes B very broad bearings on the under side of the bottom of the wagon box or body.

- 10 In each eye A² of each lever A a U-shaped shackle, K, is pivoted by a bolt, K', which shackle is formed of three parts, of which one part is held on the end of the lever A by the bolt, as stated; another part is held on the 15 under side of the side bar of the wagon-body and consists of a plate, N, provided with a downwardly-projecting semi-cylindrical neck or projection, M, having a longitudinal recess or cavity, O, forming a socket, and the slot P 20 in the bottom, which slot is at right angles to the longitudinal axis of the recess. In said recess is placed the cylinder R, which can rock on its longitudinal axis, and is provided with the downwardly-projecting stem Q, having its 25 lower end screw-threaded, said screw-threaded end being screwed into the top of the lower section of the shackle. If desired, a half-ball may be used in place of the cylinder; but I prefer to use a cylinder. The bottom sections 30 of the shackles K can swing on the ends of the levers A, and can rock on the rounded lower ends of the projections M.

The two springs of each set and their levers are placed at an angle to the transverse 35 axis of the vehicle-box, so that the outer ends of the levers A will be on the same transverse line of the vehicle-box, which transverse line is at right angles to the longitudinal axis of the box.

- 40 A vehicle provided with my improved springs rides very easily with a light or a heavy load.

Each spring is independent of the other, and each spring can be removed or replaced without disturbing the other. The springs can be used for wagons of different widths, as all that is necessary is to change their relative positions on the under side of the body.

- Having thus described my invention, I claim 50 as new and desire to secure by Letters Patent—

1. In a vehicle-spring, the combination, with

a box, of a lever having one end in said box, flat spring-plates secured to the bottom of that part of the lever in the box, and springs secured on the top of the box, the ends of the 55 springs secured on the box and on the lever being jointed together, substantially as herein shown and described.

2. In a vehicle-spring, the combination, with the box B, of the lever A, having one end in 60 said box, the tongue J, projecting upward from said lever through a slot in the top of the box, the springs D, secured to the end part of the lever A, and the springs E, secured to the top of the box E, substantially as herein shown and 65 described.

3. In a vehicle-spring, the combination, with the box B, having the side lugs, I, of the lever A, having one end in said box, the clip-yoke G, the bolts H, passed through the lugs I and 70 the clip-yoke, and the springs D and E, secured to the lever A and the box, substantially as herein shown and described.

4. In a vehicle spring, the combination, with the box B, having the lugs I and F, of the clip-yoke G, the bolts H, passed through the lugs I, and of the springs D and E, secured to the 75 lever A and the box B, substantially as herein shown and described.

5. In a vehicle-spring, the combination, with 80 the box B, having the side lugs, I, the tops of which project above the top edges of the box B, of the springs E, secured on the top of the box B between said lugs I, the lever A, having one end in the box B, the springs D, secured to that end of the lever A within the 85 box B, the ends of the springs D and E being jointed together, and of bolts passed through the lugs I, for holding the box B to the under side of the vehicle-box, substantially as herein 90 shown and described.

6. The combination, with a plate provided with a neck or projection having a cavity or recess, of a ball or cylinder in said recess, and provided with a screw-stem projecting from 95 the bottom of the neck or projection, and of a shackle-piece in which the said stem is screwed, substantially as herein shown and described.

JAMES ROBERT WRIGHT.
